[57] ABSTRACT

This invention relates generally to trays of the type used for holding paper, letters, or the like, and more particularly, to trays which are stackable upon each other.

2 Claims, 5 Drawing Figures

FIG. 1

PATENTED APR 1 1975

FIG. 5

STACKABLE TRAY

In the usual configuration, trays of the above type have been stacked upon each other in order to provide plural compartments for diverse material, e.g., various forms, stationary, etc. In the past, these stacked trays have been held together by means of one or more mating tongue and groove or peg and hole stacked configurations. Thus, a plurality of trays may be stacked by mating each additional tray to either the top or bottom of an existing tray stack. This form of construction has the inherent disadvantage of requiring plural supporting points around the periphery of each tray, thus making impossible a cantilever configuration wherein adjacent trays contact each other only at the rear portion of each tray. Access to all but the uppermost stacked tray is thereby limited to entry only from the forward opening of each tray. In addition, lack of any fastening means between trays results in an unsecure structure, wherein trays may be inadvertently dislodged from their normal positions within a given stacked array.

SUMMARY OF THE INVENTION

Accordingly, an object of this invention is to provide a new and improved stackable tray assembly.

Another object of the invention is the provision of a new and improved stackable tray assembly having increased rigidity.

Still another object is the provision of a new and improved stackable tray assembly of uncomplicated design.

Briefly, in accordance with a preferred embodiment of the invention, these and other objects are attained by providing each supporting at least one supporting bracket which is detachably fastened to the underside of an associated upper tray and downwardly extended to engage the upper side of a lower adjacent tray. Clamping means are provided to detachably secure adjacent trays by means of longitudinal compression upon the supporting bracket.

DESCRIPTION OF THE DRAWINGS

The invention is described in detail below with reference to the accompanying drawings, wherein:

FIG. 1 is a perspective view of the underside of a stackable tray and of an associated supporting bracket in detached configuration;

FIG. 2 is a perspective view of a stacked tray assembly;

FIG. 3 is a side view in section of a portion of the two stacked trays shown in FIG. 2 illustrating the insertion of the spring clamp;

FIG. 4 is a side view in section similar to FIG. 3 subsequent to insertion of the spring clamp; and

FIG. 5 is a sectional view along line 5—5 in FIG. 4.

DESCRIPTION OF THE PREFERRED EMBODIMENT

Referring to the figures, a stacked tray assembly comprising two identical trays is illustrated. It is understood, however, that any number of trays may be used, and indeed it is this facility to increase and decrease the number of trays quickly to obtain a rigid assembly which characterizes the present invention. The two trays 5 and 5' are each formed of molded plastic having a planar bottom wall 6 and side walls 7 which are canted inwardly towards each other. Of course other

tray configurations may be used within the scope of the present invention.

Each tray has a pair of guides 18 integrally provided on the downwardly facing surface of bottom wall 6. In the present embodiment these guides are formed on respective ones of a pair of extruded ledges or shoulders 12 which extend from the rear edges of the tray tapering toward each other terminating in a shoulder 30. A planar wall 13 is integrally formed with and at right angles to shoulders 12 and provides a rearward boundary for any material placed on the respective tray.

A pair of generally L-shaped supporting brackets 10 (only one shown) have dovetail ways 22 formed in their short legs which correspond in shape with the guides 18. A tab 24 is provided at the free end of the long leg of each bracket 10. The long leg preferably has a U-shaped cross-section for strength and rigidity. As shown in FIG. 1, the bracket 10 is fitted over guide 18 while the second supporting bracket (not shown) engages the remaining dovetailed guide in a like manner. The upwardly facing surface of each bottom wall 6 has a pair of slots 20 (FIGS. 3 and 4) formed therein which receive the tabs 24 extending from the respective brackets 10.

A pair of channels 16 are provided on the side edges of wall 13. Each channel has an opening 26 therethrough formed below the plane of rear wall 13 (FIGS. 3 and 4). The lower edge of each channel has a depending portion 31 which interlocks with a recess 33 formed in the upper edge of the channel which is associated with the tray stacked immediately below. Upon stacking the trays upon brackets 10, the channels are aligned. An elongate spring clamp 14 having a generally C-shape has its ends inserted through openings 26 in the respective upper and lower channels. When in place, the spring clamp 14 holds trays 5 and 5' together by means of compression longitudinally applied to the supporting bracket 10.

In the preferred embodiment of the invention, a pad 28 is provided on each of the shoulders 12 of each tray. A non-slip material (e.g., felt or rubber) is used for this purpose. The bottom tray in a given stack will thus rest upon its two pads 28 and the forward shoulder 30.

There are many possible variations of the basic invention. The number of supporting brackets employed may vary depending upon the desired structural rigidity. Both the number and the configuration of the clamping means may vary, such number not necessarily being restricted to the number of supporting brackets. While the figures illustrate the use of spring clamps 14 inserted through openings in aligned channels which are located adjacent to each bracket 10, alternate clamping means may be employed. For example, a single spring clamp may be inserted through guide holes located midway along the back sides of each tray. However, it is advantageous to have the spring clamp substantially adjacent to the support brackets so that the compressive force exerted thereby is applied to the support brackets 10, thus providing optimal rigidity and stability to a stacked array of trays.

What is claimed is:

1. A stackable tray assembly comprising:
at least two vertically adjacent trays designated an uppermost tray and a lowermost tray, each of said trays including a bottom wall; and

at least one generally L-shaped bracket, said bracket being detachably fastened solely to said adjacent trays;

at least one extruded shoulder extending downwardly from the underside of the bottom wall of each of said trays, said shoulder of the lowermost tray being formed so as to serve as a base for the said tray;

at least one dovetailed guide appended to said shoulder of the uppermost tray; said bracket having at least one dovetailed channel to cooperate with said dovetailed guide;

a tab located at the base of said supporting bracket, said tab extending downwardly; the upper surface

of the bottom wall of the lowermost tray having a recess to cooperate with said tab.

2. A stackable tray assembly as recited in claim 1, each of said trays including a rear wall having at least one opening therein, at least one elongate spring clamp having a generally C-shaped construction having two arms and a bridge portion, one arm of said clamp passing through said opening in the rear wall of the uppermost tray, the other arm of said clamp passing through said opening in the rear wall of the lowermost tray, whereby adjacent trays are compressed against said supporting bracket.
